UNITED STATES PATENT OFFICE.

TOMAS GONZALEZ Y SEBASCO, OF HABANA, CUBA.

LINE-PROTECTOR FOR TELEGRAPH AND TELEPHONE SYSTEMS.

1,111,574.

Specification of Letters Patent.

Patented Sept. 22, 1914.

Application filed May 25, 1914. Serial No. 840,778.

To all whom it may concern:

Be it known that I, TOMAS GONZALEZ Y SEBASCO, a citizen of the Republic of Cuba, and a resident of Habana, Cuba, have invented a new and Improved Line-Protector for Telegraph and Telephone Systems, of which the following is a full, clear, and exact description.

This invention relates to protector devices of the spark arrester type for telegraph, telephone or other electric systems, whereby the electric instruments are protected against high voltage charges accompanying thunder storms or other electric disturbances.

The general object of the invention is to improve and simplify the construction and operation of lightning arresters of that type including fuse wires or equivalent means so as to be reliable and efficient in use, comparatively simple and inexpensive to manufacture, and so designed that new fuses can be applied, even during the presence of a storm, without danger to the operator.

Another object of the invention is the provision of a novel arrangement of means whereby the burning of the fuses will cause the closing of circuit closing means, whereby communication through the main line wires will not be interrupted, such circuit-closing means being mounted on a removable section of the device which can be readily taken off during the presence of a storm without danger to the operator, for the purpose of putting in new fuses, it being necessary, however, to suitably preserve the continuity of the line circuit by the use of a plug or equivalent means, so that communication will not be interrupted through the line circuit while new fuses are being applied.

With such objects in view, and others which will appear as the description proceeds, the invention comprises various novel features of construction and arrangement of parts which will be set forth with particularity in the following description and claims appended hereto.

In the accompanying drawing, which illustrates one embodiment of the invention, and wherein similar characters of reference indicate corresponding parts in all the views, Figure 1 is a perspective view of the protective device with the fuse-carrying sec-

tion separated from the base but about to be applied thereto; Fig. 2 is a bottom plan view of the base for showing the cross-connecting wires, whereby the main line wires can be connected together when the fuses blow or when the removable section is taken off for replacing the fuses; Fig. 3 is a perspective view of one of the circuit closing contacts to which a fuse is connected; Fig. 4 is a detail sectional view showing the manner of electrically connecting the parts of the base and removable sections of the device together; and Fig. 5 is a diagrammatic view of the circuit connections.

Referring to the drawing, A designates the base section of the apparatus and B the removable fuse-carrying section. The base section A is shown as consisting of a plate 1 of insulating material having a recess 2 into which is set the rectangular plate 3 of the section B, such plate 3 being also of insulating material. The section A has binding posts 4 and 4^a, to which the main line wires 5 and 5^a, Fig. 5, are connected, and the base section is also provided with binding posts 6 and 6^a, to which the local wires 7 and 7^a are connected. The binding posts 4 and 4^a are connected respectively with the binding posts 6 and 6^a by current conducting parts arranged on the sections A and B. Metal strips 8 and 8^a are fastened to the top surface of the plate 1, and the extremities are bent downwardly into the recess 2 to form spring contacts 9 and 9^a, and the binding posts 6 and 6^a are connected with metal pieces 10 and 10^a which are bent downwardly into the recess 2 to form spring contacts corresponding to 9 and 9^a. On the ends of the section B are contact members 11, 11^a and 12, 12^a, which have portions disposed in the end surfaces of the plate 3 in such a manner that they are engaged with the contacts 9, 9^a and 10, 10^a, respectively. The spring contacts on the base section A normally project from the end walls of the recess 2, as clearly shown in Fig. 4, so that when the section B is inserted in such recess the spring contacts will make good electrical connections with the contacts on the section B, which section has an insulated handle b, whereby it can be easily applied to or removed from the base section A. Pivotedly mounted on the upper portions of the con-

tacts 11, 11^a, are contact levers 13 and 13^a, which have binding posts 14 and 14^a to which are fastened respectively fuse wires 15 and 15^a, which latter are in turn respectively connected with binding posts 16 and 16^a of the contacts 12 and 12^a. The levers 13 and 13^a are each provided with a spring 17 which is normally under tension when the fuse is intact, but when a fuse blows, the lever normally restrained thereby will be actuated by its associated spring so as to engage a fixed contact on the section A. The fixed contacts for the lever contacts are designated 18 and 18^a and are mounted on the section A adjacent the edge of the recess 2. These fixed contacts 18 and 18^a are normally insulated from each other by being spaced apart, but they can be connected together by a spring plug 19 being inserted in sockets 20 arranged in the plate A at a point between the fixed contacts, whereby the plug will engage the edges of the latter.

Associated with the contacts 18, 18^a is a grounding plate 21 which has a serrated edge 22 disposed adjacent the serrated edges 23 of the contacts 18 and 18^a, whereby spark gaps are provided across which electrical discharges from either line flow to the ground. This plate 21 has a binding post 24 to which a ground wire 25 is connected, as shown in Fig. 4. Between the lateral edges of the plate 21 and the contact strips 8 and 8^a are sockets 26 and 26^a, whereby either of the main line wires may be grounded by the insertion of the plug 19 in the desired socket. Normally the plug when not in use is inserted in a socket 27 provided in the plate 21, so that the socket is handy for use at all times. As shown in Fig. 2, the under side of the plate 1 is provided with cross-connections or wires 28 and 29 which respectively connect the binding posts 4 and 4^a with the fixed contacts 18, 18^a, whereby the line wires 5 and 5^a can be directly connected when either or both fuses burn out, or when the plug 19 is inserted between the contacts 18 and 18^a.

From the foregoing description taken in connection with the accompanying drawing, the advantages of the construction and method of operation will be readily understood by those skilled in the art to which the invention appertains, and while I have described the apparatus which I now consider to be the best embodiment thereof, I desire to have it understood that the apparatus shown is merely illustrative, and that such changes may be made when desired as are within the scope of the appended claims.

Having thus described my invention, I claim as new and desire to secure by Letters Patent:

1. A protective apparatus of the class described, comprising a base section having contacts for connection with circuit wires,

a removable section having contacts engaging the first-mentioned contacts, a movable contact connected with one of the contacts of the removable section, a fuse connected with the movable contact and with the other contact of the removable section, a fixed contact on the base section arranged to engage with the movable contact when the fuse burns out, and a grounded member on the base section and spaced from the said fixed contact to form a gap across which an electric discharge takes place. 70

2. A protective apparatus of the class described, comprising a base section having a recess, a plurality of contacts fastened thereto and having portions extending into the recess, means for connecting the contacts at one end with the main circuit wires and contacts at the opposite end with local circuit wires, a removable section fitting in the said recess and having contacts engaging the contacts on the base section, spring-pressed movable contacts mounted on the removable section and each connected with a contact thereof, fuse wires extending from the movable contacts to the other contacts of the removable section, fixed contacts on the base section normally insulated from each other and associated with the respective movable contacts to be engaged thereby, 90 a grounded member on the base section disposed adjacent the fixed contacts to form therewith gaps across which electric discharges take place, and cross-connections between the fixed contacts and the said contacts of the base section to which the main circuit wires are connected. 95

3. A protective apparatus of the class described comprising a base section having binding posts for connection with main line wires and binding posts for local line wires, fixed contacts, cross-connections between the main line wires, binding posts and the fixed contacts, a grounded member on the base section and forming with the fixed contacts gaps across which electric discharges take place, means adapted to be applied to the fixed contacts for electrically connecting them, in combination with a removable section having means for electrically connecting corresponding binding posts for the main and local wires together, and each means including a fuse, and a movable contact normally restrained by the fuse and adapted to engage a corresponding fixed contact on the base section when the fuse burns. 110

4. A protective apparatus of the class described comprising a base section including means for connection with main and local circuit wires, grounding means for the main circuit wires and including spark gaps, a removable section normally connecting the main circuit wires with the corresponding local circuit wires and including a fuse re- 120 125 130

straining means for connecting the main line wires together when a high potential flow through either or both line wires burns the fuses, and means for connecting the main line wires together when the removable section is removed for the application of new fuses.

In testimony whereof I have signed my name to this specification in the presence of two subscribing witnesses.
